United States Patent Office

Des. 180,951
Patented Sept. 10, 1957

180,951

BASKET

Nathaniel Hyman, Hewlett, N. Y.

Application February 7, 1957, Serial No. 44,787

Term of patent 7 years

(Cl. D58—4)

The figure is a front perspective view of a basket, showing my new design.

I claim:

The ornamental design for a basket, substantially as shown.

References Cited in the file of this patent

UNITED STATES PATENTS

D. 29,807	Cummings	Dec. 13, 1898
1,535,944	Prange	Apr. 28, 1925